UNITED STATES PATENT OFFICE

156,676

LIQUID SPRAYING DEVICE

Leo David Joseph Skidmore, London, Ontario,
Canada, assignor to Prel Incorporated, East
Orange, N. J., a corporation

Application February 28, 1948, Serial No. 144,817

Term of patent 3½ years

(Cl. D62—2)

To all whom it may concern:

Be it known that I, Leo David Joseph Skidmore, a citizen of Canada, residing at London, in the county of Middlesex and Province of Ontario, Canada, have invented a new, original, and ornamental Design for Liquid Spraying Device, of which the following is a specification, reference being had to the accompanying drawing, forming part thereof.

Figure 1 is a top plan view of a liquid spraying device embodying my new design;

Figure 2 is a side elevation;

Figure 3 is a bottom plan view;

Figure 4 is a front view; and

Figure 5 a rear view thereof.

I claim:

The ornamental design for a liquid spraying device, as shown.

LEO DAVID JOSEPH SKIDMORE.
